UNITED STATES PATENT OFFICE.

CHARLES E. CARPENTER, OF PHILADELPHIA, PENNSYLVANIA.

COMPOSITE LEATHER BELT.

1,160,040.

Specification of Letters Patent.

Patented Nov. 9, 1915.

Application filed December 7, 1914. Serial No. 875,894.

To all whom it may concern:

Be it known that I, CHARLES E. CARPENTER, a citizen of the United States, residing in Philadelphia, Pennsylvania, have invented certain Improvements in Composite Leather Belts, of which the following is a specification.

My invention relates to composite or built-up belts of leather; and the object of my invention is to provide an improved belt of this character in which I combine leather prepared by the well known vegetable tannage with leather made by mineral tannage or, as it is more familiarly known "chrome tannage".

My improved belt is made of a plurality of plies of leather, two or more as the case may be, one of which plies is of vegetable tanned leather. My improved composite belt made of vegetable and mineral tanned leather possesses a number of peculiar advantages. In the first place, while leather made by mineral tannage is tougher, stronger and more supple and yielding than leather made by vegetable tannage, it is also susceptible of greater stretch hence, except in the case of very heavy hides, a belt made wholly of mineral tanned leather is liable to stretch excessively and to narrow to such an extent as to substantially destroy its value when employed as a belt or for similar purposes. Vegetable tanned leather, on the other hand, is much stiffer, has relatively little stretch with no tendency to narrow in use, but lacks suppleness and tends to crack on the grain side when passing around small pulleys. By combining these respective leathers in the making of my improved composite belt, I take advantage of the qualities which make them peculiarly valuable and produce a belt that partakes of or possesses the virtues of both kinds of leather and avoids their deficiencies.

In the use of leather belts there are times and conditions when a tight hold or grip upon the pulley, without slippage, is absolutely essential to the proper operation of the belt. Under other conditions it is of material advantage for a certain amount of slip to occur; there being some instances where it is absolutely necessary that the belt should slip at intervals in order that the proper operation of the structure with which it is used may be effected. In using my two-ply composite belt, therefore, the mineral tanned side may be in engagement with the pulley where no slip is required

or desired, and the vegetable tanned leather may be in engagement with the pulley when conditions require or it is desired that slip shall take place between the belt and the pulley. Further, by the use of a layer of mineral tanned leather I am able to secure a better adherence to the pulley and effect a considerably greater pull per square inch of contact with the pulley than under the best conditions with belts made of vegetable tanned leather. Should slip occur when the mineral tanned leather side of the belt is in contact with the pulley, there will be less danger of burning, since the mineral tanned leather is capable of withstanding a temperature considerably higher than leather tanned by any of the vegetable processes.

These and other features of my invention are more fully described hereinafter, reference being had to the accompanying drawings, in which:

Figure 1, is a sectional view of an ordinary composite belt made wholly of vegetable tanned leather; Fig. 2, is a similar sectional view of a two-ply composite belt made in accordance with my invention; Fig. 3, is a sectional view of one form of three-ply composite belt made in accordance with my invention, and Fig. 4, is a sectional view of another form of three-ply composite belt made in accordance with my invention.

In Fig. 1, which shows a section of an ordinary composite leather belt as heretofore made, the grain sides of the two layers 1, 1, of vegetable tanned leather form the outer or external surfaces of the belt, while the flesh sides or surfaces are secured together by any suitable cement that will insure proper engagement and contact throughout their length and produce a structure of the desired characteristics and capable of performing the desired functions.

In Fig. 2, which shows a sectional view of my improved belt, 1 represents a layer of leather made in the ordinary manner with a vegetable tannage, which produces a well known type of leather such for instance as that employed in making the composite belt shown in Fig. 1, and 2 is a section of mineral tanned leather; the two sections of vegetable and mineral tanned leather being placed with their flesh sides in contact and secured together by cement of proper character or other suitable means that will insure permanent connection of said leather sections for the purpose desired.

In preparing a three-ply belt, such as

shown in Fig. 3, I prefer to employ a central part or core 1 of vegetable tanned leather, which is faced on both sides with plies 2 of mineral tanned leather. By this construction I am enabled to produce a belt having a high degree of suppleness, and further, one that is not susceptible of stretch; at the same time the belt so made will not crack or split; even when employed with 10 pulleys of small size. In some instances I may employ two layers of vegetable tanned leather with a single layer of mineral tanned leather at one side as clearly illustrated in Fig. 4.

15 A composite belt which includes a ply of mineral tanned leather and a ply of vegetable tanned leather has many advantages; that is to say, the vegetable tanned leather helps to correct the defects of the mineral 20 tanned leather, and the mineral tanned leather aids in correcting the defects of the vegetable tanned leather. Mineral tanned leather when used by itself has a greater tendency to stretch than vegetable tanned 25 leather because it does not have sufficient body or firmness to enable it to hold its width under tension. The vegetable tanned leather, however, having firmness and great body, when cemented to the mineral tanned 30 leather, enables the latter to hold its full width and therefore avoid stretch.

The mineral tanned skin is materially softer than the vegetable tanned skin, and is particularly desirable for contact with 35 the pulley when slippage is to be avoided. While this mineral tanned leather is also much tougher than the vegetable tanned leather, any tendency of the same to stretch, due to its softness, would be resisted by the 40 section of vegetable tanned leather to which it is firmly secured, with the result of attaining all of the advantages possessed by a belt made of the best vegetable tanned leather, whether composite or not, while 45 avoiding all of the disadvantages of the same. By reason of the supple character of the mineral tanned leather, it will have a tendency to cling more tightly to the pulley, and there will be very much less likelihood 50 of any slip occurring. In case of slip, however, the danger of burning would be much less since the mineral tanned leather will stand a much higher temperature than vegetable tanned leather: probably as much as 55 a difference of 100° F. Such a belt, while having greater strength than a composite or double belt made of vegetable tanned leather, will be considerably lighter in weight and thereby effect economy in the 60 load; that is to say, there will be less weight of belt to be pulled.

A great disadvantage in connection with vegetable tanned leather belts when made

of a plurality of plies is because the grain side of the belt is so apt to crack when the 65 belt is bent, especially when passing around a small pulley. This is entirely avoided by the use of a mineral tanned skin as one of the plies or layers.

My improved composite belt will be far 70 more supple than any double or triple composite vegetable tanned leather belt heretofore made, and hence will give better service when used in connection with small pulleys, particularly those of electric generators, and 75 others driven at high speeds. Finally, its economy in weight with a gain in strength and efficiency of action will materially enhance its value without increasing the cost.

To sum up, my improved composite belt, 80 made of independent layers or plies of vegetable tanned leather and mineral tanned leather cemented together, is capable of wider use than the ordinary composite belts; it is stronger; it will not crack in making 85 short turns, passing over small pulleys and the like; it will not slip when the face of mineral tanned leather is in contact with the pulley but can slip when the vegetable-tanned leather face is in contact with the 90 pulley; and finally, while having a greater degree of suppleness, it will not lose its width in use, nor stretch.

I claim:

1. A composite belt made up of a section 95 of vegetable tanned leather, and a section of mineral tanned leather permanently secured together.

2. A composite belt made up of a plurality of sections of mineral tanned leather 100 and vegetable tanned leather, permanently secured together.

3. A composite belt made up of a section of vegetable tanned leather, and a section of mineral tanned leather, said sections having 105 their grain sides outermost with their flesh sides permanently secured together.

4. A composite belt made up of a section of vegetable tanned leather, and a section of mineral tanned leather having the flesh 110 sides or surfaces of the same permanently cemented together.

5. A composite belt made up of a section of vegetable tanned leather, and a section of mineral tanned leather permanently secured together, the section of mineral tanned leather being less in thickness than the section of vegetable tanned leather. 115

In testimony whereof, I have signed my name to this specification, in the presence of 120 two subscribing witnesses.

CHAS. E. CARPENTER.
